CONTROL APPARATUS FOR REVERSIBLE MOTORS

Frederick R. Farrow, Jr., Audubon, N. J., assignor, by mesne assignments, to Philco Corporation, Philadelphia, Pa., a corporation of Pennsylvania

Application March 31, 1944, Serial No. 528,898

10 Claims. (Cl. 172—340)

1 This invention relates to a novel system for controlling a reversible motor, and more particularly to novel means for effecting controlled periodic reversal of the motor. The invention is particularly useful in the control of an electric motor-driven mechanism, such as the scanning antenna employed in radio detecting and ranging (radar) systems and the like.

In certain systems of this character, the scanning equipment is driven by an electric motor which is, or may be, periodically reversed so that the scanning equipment is driven back and forth across a desired sector. In some of the systems heretofore proposed, it has been necessary to utilize two motors, one for driving the controlling mechanism, and one for driving the scanning equipment. In these prior systems the apparatus for controlling the scanning equipment had to be designed so as to compensate for the normal tendency of a motor to rotate better in one direction than in the other, which tendency caused the apparatus to "creep" in the direction of more efficient motor operation.

It is an object of the present invention to provide an improved and simplified control mechanism for a reversible motor, especially in a system of the above-mentioned character.

Another object of the invention is to provide motor-driven control apparatus for motor-driven scanning equipment which shall have no tendency to "creep."

Other objects and advantages will become apparent as the invention is described in connection with the accompanying drawing, the single figure of which is a diagrammatic illustration of a typical control system embodying the principles of the invention.

In the drawing, a reversible motor 2 is provided and arranged continuously to rotate, or, alternatively, to oscillate, a mechanism such as a directional antenna, or other device, over which control of rotation and period or amplitude of oscillation is desired. In radar practice, structures of this character are commonly known as "spinners" or scanning devices, and such device is so designated in the drawing where it is represented diagrammatically by the circular figure bearing the reference numeral 4. Since the structure and operation of such apparatus is known, and may vary in detail according to the use to which it may be put, the particular apparatus driven by the motor 2 is neither specifically illustrated nor described in detail herein.

The field winding 6 of the reversible motor 2 may be connected directly to the supply line con-

ductors 8 and 10. The armature 12 of this motor is connected to the same line conductors 8 and 10 through the agency of the conductors 14 and 16, 18 and 20, and the reversing relay 22. The reversing relay 22 is preferably of the "over-center" or "latching" type. Reversing relays of this general character are well known in the art, and consequently it is deemed unnecessary to describe this device in detail. It will suffice to say that when the movable contactors 24 and 26 are drawn to the right (as shown) by energization of the relay winding 28 the said contactors will "latch" in that position, and will remain in that position until such time as the relay coil 30 is energized. At such time the contactors 24 and 26 will be drawn to the left, and will remain latched in that position until such time as relay coil 28 is energized. It will be evident from the drawing that the movable contactors 24 and 26, together with the fixed contact points 32, 34, 36, and 38, constitute a conventional reversing switch or relay. Thus, in one position of the movable contactors 24 and 26, the armature 12 of the reversible motor 2 is so connected to the line as to cause rotation of the motor in one direction, while in the other position of the movable contactors 24 and 26, the armature is so connected as to produce motor rotation in the opposite direction.

The armature or rotor 12 of the reversible motor may be mechanically coupled, by any suitable and convenient means, to the scanning device 4. In the drawing, this mechanical coupling is represented by the dashed connecting line. Also mechanically coupled to the reversible motor 2, and rotating in synchronism with the scanning device 4, is a rotating commutator 40, preferably constructed of a conducting material, and bearing a suitable contact element 42. Concentrically arranged around the rotating the rotating commutator 40 are a plurality of fixed contact points 44, 46, 48, 50, 52, and 54. These fixed contact points are preferably equally spaced about the rotating commutator, and are so positioned with respect thereto that electrical contact is made between the said fixed contact points and the contact element 42 as the said element rotates past, or reaches, a given contact point. As shown in the drawing, the rotating commutator is connected by means of a conductor 56 to the conductor 10 of the line 8, 10. The specific function of the rotating commutator 40 will be described in detail hereinafter.

Each of the contact points 44, 46, etc., are connected by means of suitable conductors to the

similarly designated contact points of a pair of manually operable switches 58 and 60. Thus, by way of example, the contact point 44 associated with the rotating commutator 40 is connected by way of the conductor 62 with the contact point 44a of the switch 60, and by way of the conductors 62 and 64 with the contact point 44b of the switch 58. The switches 58 and 60 together comprise what may be referred to as a "sector selector," and they are so designated in the drawing. The 10 adjustable contact arm 66 of switch 58 is connected by way of the conductor 70 to terminal 82 of the reversing relay coil 28. Similarly the adjustable contact arm 68 of switch 60 is connected by way of conductor 72 to terminal 78 of 15 reversing relay coil 30. The other terminals, 84 and 80, of coils 28 and 30 are connected together by means of the conductor 74, and to the line conductor 8 by way of the conductor 76. Accordingly one terminal of each of the reversing relay coils 28 and 30 is connected permanently and directly to one side of the line 8, 10. Connection between the other terminals of the coils 28 and 30 and the other side of the line is made through the sector selector switches 58 and 60, and the 20 rotating commutator 40.

The component parts and connections illustrated in the drawing having now been described, the operation of the system will now be set forth. Let us assume that it is desired to so operate the 25 scanning device 4 that the sector S₁ shall be continuously scanned. As indicated, the limits of the sector S₁ are defined by the reference characters 44c and 46c. By means of the structure provided by the present invention, such operation is secured by setting the contact arms 66 and 68 of sector selector switches 58 and 60 to corresponding and similarly designated switch contact 30 points.

Thus the contact arm 68 may be adjusted to contact the contact point 46a, while the contact arm 66 is adjusted to contact the contact point 44b. These switch adjustments are illustrated in the drawing. If now the field 6 of the motor 2 is connected in the proper sense to the line conductors 8 and 10, and this is most conveniently determined by trial, the system will operate as follows. Assume that at the instant represented in the drawing the scanning device 4 and the rotating commutator 40 are being driven synchronously in a clockwise direction by the reversible motor 2. When the contact element 42 of the rotating commutator reaches the contact point 46, a connection will be completed between the line conductor 10 and the terminal 78 of relay coil 30. This connection includes the conductor 56, the rotating commutator 40, contact element 42, contact point 46, conductor 86, contact point 46a, switch arm 68, and the conductor 72. Since terminal 80 of the relay coil 30 is already connected to the other side of the line by way of the conductors 74 and 76, the coil 30 is now energized from the line, and consequently the movable contactors 24 and 26 are moved from the position illustrated to their left-hand position, where they make contact with stationary contacts 32 and 36 respectively, thus reversing the connections between the armature 12 and the line conductors 8, 10, and thereby reversing the direction of rotation of the motor. The direction of rotation of the scanning device 4 and the rotating commutator 40 are, of course, also reversed, and consequently the rotating commutator 40 now proceeds to rotate in a counter-clockwise direction. This 55 it continues to do until the contact element 42 reaches

and makes contact with contact point 44. When this occurs a connection is completed between the line conductor 10 and terminal 82 of relay coil 28. This connection includes the conductor 56, the rotating commutator 40, contact element 42, contact point 44, the conductors 62 and 64, switch arm 66, and the conductor 70. Since the terminal 84 of relay coil 28 is already connected to line conductor 8 by way of the conductors 74 and 76, the coil 28 is energized and movable contactors 24 and 26 are moved from their left-hand position to the right-hand position shown. This effects a second reversal of the motor 2, whence the scanning device 4 and the rotating commutator 40 are also reversed and begin rotation in the clockwise direction. The foregoing train of events will now repeat cyclically so long as the contact arms 66 and 68 of the sector selector switches remain in the positions shown.

It will now be evident that by means of the present invention it is possible to establish, on the sector selector switches 58 and 60, connections corresponding to desired sector limits on the scanning device 4, and thus to effect continuous scanning over a desired sector. For example, if it is desired to sector-scan the sector S₁ included within the sector limits 52c and 54c, it is only necessary to adjust the switch arm 66 to contact the contact point 52b and to adjust the switch arm 68 to contact the contact point 54a. Larger sectors may be scanned by adjusting the switch arms 66 and 68 to the contact points corresponding to the limits of the desired sector. Where six contact points are provided, as in the illustration, the smallest sector which can be scanned is a 60° sector. If smaller sectors are desired it is, of course, necessary only to increase the number of contact points associated with the rotating commutator and with the two sector selector switches.

Although it will normally be desired to scan sectors of substantially less than 180°, it may, under certain circumstances, be useful to scan 45 sectors of greater than 180°. Such large sectors are as readily scanned with the apparatus illustrated as are the smaller sectors. As has already been stated, with the specific adjustment illustrated in the drawing, sector scanning of the device 4 is effected over the sector S₁. If, now, the relative positions of the sector selector switches are reversed, i. e., if contact arm 66 is moved to contact 46b and contact arm 68 moved to 50 44a, the scanning device 4 will sector-scan the sector S₃. It will be observed that the sector S₁ has the same limits as the sector S₁, but that sector S₃ is the complement of sector S₁.

The scanning apparatus of the drawing has been described, so far, only with reference to its 55 operation as a sector scanning system. As was indicated at the outset, the system illustrated in the drawing is also adapted to effect continuous rotation, in either direction, of the scanning device 4. To this end there may be provided a switch 88 (shown in its closed position) in the conductor 78. This conductor normally connects one terminal of each of the relay coils to the line conductor 8. When the switch 88 is opened the relay coils can no longer be energized through the rotating commutator and sector selector circuits, and consequently rotation of the scanning device 4 continues in the direction it had at the moment the switch 88 was opened. The operator can, if he desires, open the switch to give continuous rotation in a selected direction by sim-

ply observing the movements of the scanning device 4 before he opens the switch 88.

It will be apparent that the invention is not limited to the specific purpose illustrated and described but may be utilized in any instance where it is desired to effect adjustable periodic reversal of motor-driven equipment. It will also be apparent that various modifications within the scope of my invention will occur to those skilled in the art. Therefore I do not limit it to the specific form and arrangement of the apparatus diagrammatically illustrated in the drawing.

I claim:

1. Apparatus for actuating a rotatable device back and forth through any one of a plurality of predetermined sectors, comprising a reversible motor connected to said device to drive the same, rotary switching means driven by said motor synchronously with said device, selector switching means manually-settable to determine the location and amplitude of the sector through which said device is to be actuated, and means controlled by both of said switching means to cause reversing of said motor automatically as said device reaches the limits of the selected sector.

2. Apparatus for actuating a rotatable device back and forth through any one of a plurality of predetermined sectors, comprising a reversible motor connected to said device to drive the same, rotary switching means driven by said motor, means controlled by said rotary switching means to automatically reverse the rotation of the driving motor as the limits are reached of the sector through which said device is to be actuated, and selector switching means connected to both of the aforesaid means for determining the desired sector and the amplitude thereof.

3. Apparatus for actuating a rotatable device back and forth through any one of a plurality of predetermined sectors, comprising a reversible motor connected to said device to drive the same, rotary switching means driven by said motor, electromagnetic switching means energized by the operation of said rotary switching means to automatically reverse the rotation of the driving motor as the limits are reached of the sector through which said device is to be actuated, and selector switching means connected to both of the aforesaid means for determining the desired sector and the amplitude thereof.

4. Apparatus for actuating a rotatable device back and forth through any one of a plurality of predetermined sectors, comprising a reversible motor connected to said device to drive the same, rotary switching means driven by said motor, comprising a set of stationary contacts engageable by a movable contact, selector switching means interconnected with said rotary switching means and having stationary contacts complementary to and respectively connected with the stationary contacts of said rotary switching means, settable contacts selectively engageable with said complementary contacts to determine the amplitude and location of the sector through which said device is to be actuated, and means operable by said rotary switching means to automatically reverse the rotation of the driving motor as the limits are reached of the selected sector.

5. Apparatus for actuating a rotatable device back and forth through any one of a plurality of predetermined sectors, comprising a reversible motor connected to said device to drive the same, an electromagnetically-operated reversing switch for said motor, selector switch means controlling

the movement of said reversing switch into "forward" position and into "reverse" position, rotary switching means driven by said motor for operating said reversing switch, and complementary electrically-identical stationary contact means in said selector switch means and said rotary contact means, whereby the setting of said selector switch means predetermines the operative contacts of said rotary switching means and thereby the sector through which said device is to be actuated.

6. Apparatus for actuating a rotatable device back and forth through any one of a plurality of predetermined sectors, comprising a reversible motor connected to said device to drive the same, a rotary switch driven in synchronism with said device by said motor and having a plurality of fixed contacts engageable by a movable contact at the boundaries of a plurality of different sectors to complete a circuit for causing reversal of said motor, and manually-settable means to select the circuits to certain of said fixed contacts to determine the sector through which said device is to be actuated.

7. Apparatus for actuating a rotatable device back and forth through any one of a plurality of predetermined sectors, comprising a reversible motor connected to said device to drive the same, a rotary switch driven in synchronism with said device by said motor and having a plurality of fixed contacts engageable by a movable contact at the boundaries of a plurality of different sectors, electromagnetic reverse switching means operated by the engagement of said fixed and movable contacts for causing forward and reverse operation of said motor, and manually-settable means to select the circuits to certain of said fixed contacts to determine the sector through which said device is to be actuated.

8. Apparatus for actuating a rotatable device back and forth through any one of a plurality of predetermined sectors, comprising a reversible motor connected to said device to drive the same, a rotary switch driven in synchronism with said device by said motor and having a plurality of fixed contacts engageable momentarily by a movable contact at the boundaries of a plurality of different sectors to complete a circuit, and reversing means operable by the circuit completion for changing the direction of rotation of said motor and for maintaining the circuit to the motor in closed condition until the opposite side of the desired sector is reached.

9. Apparatus for actuating a rotatable device back and forth through any one of a plurality of predetermined sectors, comprising a reversible motor connected to said device to drive the same, rotary switching means driven by said motor synchronously with said device, said switching means including a rotating contact and a plurality of fixed contacts engageable by said rotating contact, a manually-adjustable sector selector device having fixed contacts corresponding to those of said rotary switching means, and also having rotatable contact means adapted to be placed in engagement with the associated fixed contacts, electrically-operable means for effecting reversal of operation of said motor, and circuit connections between said rotary switching means, said sector selector device and said reversing means for controlling the latter so as to effect actuation of said rotatable device through a sector determined by the setting of the sector selector device.

10. Apparatus for actuating a rotatable device

back and forth through any one of a plurality of predetermined sectors, comprising a reversible motor connected to said device to drive the same, rotary switching means driven by said motor synchronously with said device, said switching means including a rotating contact and a plurality of fixed contacts engageable by said rotating contact, a manually-adjustable sector selecting contact, a sector selector device having two sets of fixed contacts each corresponding to those of said rotary switching means, and also having two rotatable contacts adapted to be placed in engagement with the associated fixed contacts according to the limits of the sector through which it is desired to actuate said rotatable device, electrically-operable means 15 for effecting reversal of operation of said mo-

tor, and circuit connections between said rotary switching means, said sector selector device and said reversing means for controlling the latter so as to effect actuation of said rotatable device through a sector determined by the setting of the sector selector device.
